UNITED STATES PATENT OFFICE

THOMAS SCOTT GRIEVE, OF LEICESTER, ENGLAND

CIRCULAR KNITTING MACHINE

Application filed June 28, 1928, Serial No. 288,909, and in Great Britain September 2, 1927.

This invention relates to circular knitting machines of the type having superposed needle cylinders which rotate within stationary cam boxes and concerns more particularly, though not exclusively, such machines adapted for the production of seamless hosiery.

The object of the invention is to provide in or for a circular knitting machine of the aforesaid type a form of splicing mechanism which will ensure the splicing yarn being conveyed to the needles by the main yarn.

In the specification of my British Patent No. 13081 of 1907 I have described splicing mechanism which has as its essential feature means for twisting the splicing thread round the main thread so that, as the latter was drawn in by the needles, the splicing thread was taken with it thereby ensuring introduction of said splicing thread to the needles.

This twisting or wrapping of the one thread about the other is found to give most satisfactory results and up to the present the mechanism forming the subject of my British patent aforesaid has always been used in superposed needle cylinder knitting machines of the kind wherein the said cylinders were stationary.

Seamless hosiery machines having superposed needle cylinders which rotated were not known at the date of my British Patent No. 13081 of 1907 and were not introduced to the trade until some years later. In connection with such machines various problems have presented themselves and some of these have been found difficult to solve. One difficulty experienced has been to provide a splicing mechanism which operated with certainty.

My present invention consists in applying or adapting the splicing mechanism of the aforesaid British patent, or splicing mechanism substantially like this, to a superposed cylinder knitting machine of the revolving cylinder type.

In carrying out the invention I use a rotating funnel or like member with a trapper device such as described in the specification aforesaid on a revolving cylinder knitting machine said funnel or member being driven

such as by gearing or friction or both preferably by or from the top needle cylinder.

In general form and construction and also in operation the funnel or member is conveniently the same or substantially the same as described in the prior specification referred to.

In applying this mechanism to a machine of the revolving cylinder type I find it convenient to mount the funnel rotatably in the top bearing plate of the machine and to impart the necessary rotation either by friction drive from the top needle cylinder or by a pinion meshing with a gear wheel on the top needle cylinder.

In further describing the invention reference will be made to the accompanying drawings, wherein,

Figure 1 is a plan view of a practical example of the invention.

Figure 2 is a side elevation of the same.

Figure 3 is a sectional elevation of the splicing mechanism taken along line III—III of Figure 1, and

Figures 4 to 8 are views illustrating different stages in the operation of the splicing mechanism.

Fig. 9 is a diagrammatic side elevation of a double cylinder knitting machine having the splicing mechanism applied thereto. Figure 10 is a detail view of the spring controlling the trapper.

In the constructional embodiment illustrated, the stalk or shank 1 of the funnel 2 is rotatably mounted in a sleeve 3 in turn rotatably mounted in a bush 4 in the top bearing plate 5 of a circular knitting machine of the type aforesaid. The sleeve 3 has secured to its lower end by a key 6 a gear wheel 7 in mesh with the top cylinder gear 8 and is therefore driven continually while the machine is in operation. The funnel 2 is normally held stationary but when released, as hereinafter described, is driven frictionally by the sleeve 3. For this purpose a spring ring 9 is fixed, e. g. by a screw 9a in a groove 10 in the shank 1 of the funnel, which ring, by expansion makes frictional contact with the inside of the sleeve and thus serves to transmit the drive from

the sleeve to the funnel when the latter is free to rotate.

The rotation of the funnel is controlled by intermediate connections from the existing 5 controlling drum of the machine. To this end the funnel 2 is provided with a radially disposed pin 11 which is normally engaged and held by a projection 12 on a block 13 carried above the top plate 5 by a spring 10 controlled rod 14 adapted to be moved vertically in one direction, viz. downwards by a spring 15 and in the other direction by cam pieces on the drum.

The yarn trapping arrangement in the funnel is similar to that described in the prior 15 specification herein referred to, except that the trapper 16 is provided with a pin 17 which is engaged by the projection 12 on the block 13 for opening the trapper at the time required. The arrangement is also improved 20 by the provision of a yielding platform or step upon which the trapper presses the yarn to hold it. This platform consists of a plate 18 on a plunger 19 controlled by a spring 20, 25 the object being to more yieldingly hold the end of the splicing yarn 21 than heretofore, so that it can, after the splicing yarn has been twisted about the main yarn 22, be more easily pulled out from between the opposing 30 trapper members and thus obviate drag on the main yarn. An arm 23 is provided on the upper end of the rod 14 which engages a pin 24 on the splicing yarn guide 25 for a purpose hereinafter described. The 35 yarn guide is pivoted at 26 on a bracket 27 attached to the top plate 5.

To effect introduction of the splicing yarn at the time required a step of one of the cam pieces on the drum moves the rod 14 upwards so that the block 13 is raised to release 40 the pin 11, as shown in Figure 4, whereupon the funnel 2 is rotated frictionally by the sleeve 3 and makes one or more revolutions. Consequently the splicing yarn is twisted 45 round the main yarn and the free end thereof is also pulled from between the trapper members 16 and 18. After the funnel has made the desired number of revolutions another step on the drum cam piece moves 50 the rod 14 upwards a little further, so that another projection 28 on the block 13 is raised into the path of the pin 11, as represented in Figure 5, whereby the rotation of the funnel is arrested. The projection 28 is so arranged 55 that the funnel is brought to rest with the trapper pin 17 directly above the projection 12 as shown in Figures 5 and 6. The upward movement of the rod 14 also moves the arm 23 which imparts a downward movement to 60 the yarn guide 25 thus bringing the splicing yarn down close to the top of the trapper 16. Almost immediately another step on the drum cam piece lifts the rod still further so that 65 the projection 12 engages the pin 17 and lifts the trapper 16 as represented in Figures 7

and 8. This upward movement of the rod 14 brings down the splicing yarn guide still further. Since the trapper is now open and also by reason of the curvature (see Figures 5 to 8) of the top face of the trapper, the splicing 70 thread is caused to pass between the two trapper members 16 and 18 as illustrated in Figures 7 and 8. The block 13 is then released by the passage of the cam piece whereupon the trapper 16, under the influence of a spring 29 hereinafter described, falls and by co-operation with a cutter 30 severs the splicing 75 yarn, the end of which is again trapped between the opposing members 16 and 18 as represented in Figures 1 and 3 in readiness 80 for the next splicing operation. The splicing yarn guide is also returned to its normal position by a spring 31. The yarn guide may be provided with a finger 32 which extends over the funnel to prevent the splicing 85 yarn from ravelling.

The spring 29 is a wire spring as shown in Figure 10 having one end secured by a screw 40 to the funnel 2 and its free end engaging 90 with a slot 41 in the trapper 16.

The funnel is driven to revolve at a higher speed than the needle cylinders so as to rapidly twist the splicing yarn about the main 95 yarn.

It will be understood that the splicing thread is supplementary to the main thread; in other words, the main thread passes to the needles all the time and the additional splicing thread is run in along with the main thread when the fabric is to be reinforced.

What I claim then is:—

1. The combination with a circular knitting machine of the superposed rotary needle cylinder type, of splicing mechanism comprising a vertically disposed tubular member through which a main yarn passes to the needles, a driven sleeve within which the tubular member is normally held stationary, and means on the tubular member for trapping and severing a splicing yarn, said tubular member being driven by the sleeve, when required, to twist the splicing yarn round the main yarn, so that the latter carries the splicing 105 yarn in with it.

2. The combination with a circular knitting machine of the superposed rotary needle cylinder type of splicing mechanism comprising a vertically disposed tubular member through which a main yarn passes to the needles, a positively driven sleeve within 110 which said member is located, and whereby it is driven frictionally, means on the tubular member for trapping and severing a splicing yarn, and means for normally holding the tubular member stationary in the sleeve and operable to release same, when required, to twist the splicing yarn round the main yarn, so that it is taken in with the latter.

3. The combination with a circular knitting machine of the superposed rotary nee- 120

- dle cylinder type, of splicing mechanism comprising a vertically disposed tubular member through which a main yarn passes to the needles, a driven sleeve within which said member is located and whereby it is driven, means on the tubular member for trapping and severing a splicing yarn, and means for normally holding the tubular member stationary in the sleeve and operable automatically to release same, when required, to twist the splicing yarn round the main yarn, so that the latter will carry the splicing yarn with it to the needles, said means also serving to control the trapping and severing means, for the purpose set forth. 5
4. The combination with a circular knitting machine of the superposed rotary needle cylinder type, of splicing mechanism comprising a vertically disposed tubular member through which a main yarn passes to the needles, a driven sleeve within which said member is located and whereby it is driven, means on the tubular member for trapping and severing a splicing yarn, and means for normally holding the tubular member stationary in the sleeve and operable to release same, when required, for twisting the splicing yarn round the main yarn whereby the latter will take the splicing yarn with it, said means also serving to control the movable trapper element, and means associated with the trapper for severing the splicing yarn, for the purpose set forth. 10
5. The combination with a circular knitting machine of the superposed rotary needle cylinder type of splicing mechanism comprising a vertically disposed sleeve driven by gearing from the top needle cylinder, a tubular member located within and adapted to be driven frictionally by said sleeve, a main yarn being passed through said member to the needles, means on the tubular member for trapping and severing a splicing yarn, and means for normally holding the tubular member stationary within the sleeve and operable automatically to release same when required to twist the splicing yarn round the main yarn so that the splicing yarn is taken in with the main yarn, for the purpose described. 15
6. The combination with a circular knitting machine of the superposed rotary needle cylinder type, of splicing mechanism comprising a vertically disposed sleeve driven from the top needle cylinder, a tubular member located within the sleeve and adapted to be driven frictionally thereby, a main yarn being passed through said member to the needles, means on the tubular member for trapping and severing a splicing yarn, and a device for normally holding said member stationary within the sleeve and automatically movable step-by-step vertically first to enable the tubular member to rotate within the 20

sleeve to twist the splicing yarn round the main yarn, then to check such rotation, then to open the trapping and severing means to receive the splicing yarn, and then to enable said means to operate to trap and sever said yarn, after the required splicing operation, for the purpose herein set forth. 25

7. The combination with a circular knitting machine of the superposed rotary cylinder type, of splicing mechanism comprising a vertically disposed rotary sleeve, a tubular member within the sleeve through which a main yarn passes and which is adapted to be driven by the sleeve, a trapper device, carried by said member, said device including a movable element co-operating with a normally yieldable element, for lightly holding the end of the splicing yarn, and means for normally holding the tubular member stationary in the sleeve and operable to release same, when required, for twisting the splicing yarn round the main yarn whereby the latter will take the splicing yarn with it, said means also serving to control the movable trapper element, and means associated with the trapper for severing the splicing yarn, for the purpose set forth. 30

8. The combination with a circular knitting machine of the superposed rotary cylinder type, of splicing mechanism comprising a rotary sleeve, a tubular member within the sleeve through which a main yarn passes and which is adapted to be driven by the sleeve, a trapper device carried by said member, said device including a movable element cooperating with a yieldable element for lightly holding the end of the splicing yarn and having a cutting edge, a yieldable cutter co-operating with the movable trapper element, and a device for normally holding the tubular member stationary in the sleeve, and operable automatically with a step-by-step action first to enable said member to rotate within the sleeve when required, for twisting the splicing yarn round the main yarn, and then to open the trapping and severing means, and then to enable said means to operate to trap and sever the yarn after the required splicing operation, for the purpose herein set forth. 35

In testimony whereof I affix my signature. 40
